(57) **CLAIM**

The ornamental design for a flexible pull-up for a boot as shown and described.

DESCRIPTION

FIG. 1 is a first perspective view of a flexible pull-up in a partially raised position for a boot.

FIG. 2 is a second perspective view of the flexible pull-up in a partially raised position for a boot.

FIG. 3 is a front view of the flexible pull-up in a partially raised position for a boot.

FIG. 4 is a back view of the flexible pull-up in a partially raised position for a boot.

FIG. 5 is a first perspective view of the flexible pull-up in a lowered exterior position for a boot.

FIG. 6 is a second perspective view of the flexible pull-up in a lowered exterior position for a boot.

FIG. 7 is a front view of the flexible pull-up in a lowered exterior position for a boot.

FIG. 8 is a back view of the flexible pull-up in a lowered exterior position for a boot.

FIG. 9 is a first perspective view of the flexible pull-up in a lowered interior position for a boot.

FIG. 10 is a second perspective view of the flexible pull-up in a lowered interior position for a boot.

FIG. 11 is a front view of the flexible pull-up in a lowered interior position for a boot.

FIG. 12 is a back view of the flexible pull-up in a lowered interior position for a boot.

FIG. 13 is a first perspective view of the flexible pull-up in a fully raised position for a boot.

FIG. 14 is a second perspective view of the flexible pull-up in a fully raised position for a boot.

FIG. 15 is a front view of the flexible pull-up in a fully raised position for a boot.

FIG. 16 is a back view of the flexible pull-up in a fully raised position for a boot.

FIG. 17 is a side view of the flexible pull-up in a fully raised position for a boot and being manually engaged.

FIG. 18 is a front view of the flexible pull-up in a fully raised position for a boot and being manually engaged.

FIG. 19 is a back view of the flexible pull-up in a fully raised position for a boot and being manually engaged.

FIG. 20 is a first perspective view of the flexible pull-up in a fully raised position for a boot and being manually engaged; and,

FIG. 21 is a second perspective view of the flexible pull-up in a fully raised position for a boot and being manually engaged.

The broken line showing of parts of the drawings is included for the purpose of illustrating use and environment and forms no part of the claimed design.

1 Claim, 21 Drawing Sheets
